CLAIM

The ornamental design for TV chest, as shown and described.

DESCRIPTION

FIG. 1 is a front perspective view of a TV chest showing my new design;

FIG. 2 is a front perspective view of a TV chest showing my new design thereof; and,

FIG. 3 is a side view of a TV chest showing my new design thereof.

The top, and bottom views which are not shown, form no part of that which is claimed.

Other extraneous elements depicted in dotted lines in FIG. 1, such as the flat screen television, audio equipment, VCR device, and any other accessory elements are environmental elements only and form no part of, and are not a limitation to, the invention.

1 Claim, 3 Drawing Sheets

FIG. 1

FIG. 2

FIG. 3
